UNITED STATES PATENT OFFICE.

ANTON IVERSEN SLETTEN, OF CHRISTIANIA, NORWAY.

INTERNAL-COMBUSTION ENGINE.

1,421,594.

Specification of Letters Patent. Patented July 4, 1922.

Application filed June 16, 1920. Serial No. 389,354.

To all whom it may concern:

Be it known that I, ANTON IVERSEN SLETTEN, a subject of the King of Norway, residing at Christiania, Norway, have invented 5 certain new and useful Improvements in Internal-Combustion Engines; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 In internal combustion engines of the kind provided with a hot chamber into which is introduced a jet of oil ignited by the hot walls of the chamber, it is known to place a deflector in the path of the oil jet in order 20 to direct the oil either upwards in the hot chamber or downwards into the cylinder.

Said deflectors are and very liable to becoming overheated, so that part of the oil introduced is deposited in the form of carbon and slag on the deflector. This again 25 makes it necessary to take the deflector out for cleaning at shorter or longer intervals.

This inconvenience is obviated according 30 to the present invention by placing the deflector surface on a water-cooled tube, which goes diametrically through the hot chamber. In the preferred form the deflector surface is worked formed in the middle of a thick-walled water tube, but obviously the deflecting 35 vane or the like may also be fastened on a rod or arm provided with water-cooling means.

On the drawing illustrating one form of the invention:

40 Fig. 1 is a vertical section perpendicularly on the water tube.

Figs. 2 and 3 are vertical and horizontal axial sections through the water tube.

1 is the jet mouth piece and 2 the deflecting surfaces by means of which the oil may 45 be deflected in the known manner in an upward or downward direction, as indicated on Fig 1.

The deflecting surfaces 2 are formed by cutting away the thick walls of the tube 3, 50 so as to form substantially flat oil deflecting surfaces that will deflect oil when sprayed against them upwardly and downwardly, as clearly shown in Fig. 1. The tube 3 is substantially straight and extends 55 straight through the hot chamber commonly used with the liquid fuel type of internal combustion engine. Being straight, it is readily removable for cleaning. Being thick-walled, the deflecting surfaces 2 may 60 be cut into the wall of the tube at the desired angle whereby deflecting surfaces are formed without the use of any additional element.

In order to cool the tube 3 cooling water 65 is led into one end of it and carried away from the other end by the pipes 4. In order to control the angle of deflection, a handle 5 may be provided whereby the tube 3 may be turned so as to cause the oil to be 70 deflected in the proper direction upwardly and downwardly.

Claims.

1. In combination with an internal combustion engine of the type provided with a 75 hot chamber, a thick-walled tube running through the hot chamber from one side to the other, the wall of the tube being cut away to form upwardly and downwardly directed oil deflecting surfaces, means for 80 passing a current of cooling water through the tube, and means for spraying oil against the said oil deflecting surfaces.

2. The combination as claimed in claim 1, in combination with means for turning the 85 said tube for controlling the direction of deflection.

In testimony that I claim the foregoing as my invention, I have signed my name in presence of two subscribing witnesses.

ANTON IVERSEN SLETTEN.

Witnesses:

ROBERT H. FRAZIER,
A. B. COOK.
